(57) **CLAIM**

The ornamental design for a pointed star lug nut cover, as shown and described.

DESCRIPTION

FIG. 1 is a left side perspective view of the pointed star lug nut cover, showing my new design;

FIG. 2 is a top side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines represent portions of the structure that forms no part of the claim.
